UNITED STATES PATENT OFFICE

JULIUS LOCHMAN, OF NEW YORK, N. Y.

NECKTIE-FASTENER.

SPECIFICATION forming part of Letters Patent No. 292,929, dated February 5, 1884.

Application filed December 12, 1883. (No model.)

To all whom it may concern:

Be it known that I, JULIUS LOCHMAN, a citizen of the United States, and a resident of New York, in the county of New York and 5 State of New York, have invented certain new and useful Fastenings for Neckties, &c., of which the following is a specification.

The invention relates to an improved fastening device applied to the rear side of the 10 shield of a neck tie or scarf for permitting the attachment of same to the collar-button quickly, securely, and easily. The said device has been constructed with a view particularly of receiving the head of any of the various sizes and styles of collar-buttons now in 15 use without difficulty.

The invention will be fully understood from the description hereinafter presented, reference being had to the accompanying drawings, 20 in which—

Figure 1 is a rear plan view of the shield of a necktie having the invention attached. Fig. 2 is a view of the opposite side of the 25 shield, showing the lips by means of which the device is secured. Fig. 3 is a view of the blank from which the fastening is formed, and Fig. 4 is a section on the line $x-x$ of Fig. 1.

A denotes the necktie-shield, and C the 30 fastening which is the subject of this application. The fastening C will be blanked from sheet metal by the well-known punch-and-die processes. It consists of a box-like formation, closed at its sides and smaller end by the flanges a, its lower end being entirely open. 35 The end flange a is pointed, and side flanges a have cut upon them lips b, which pointed end and lips penetrate the shield B, and are bent over on the opposite side thereof, for the purpose of holding the attachment in place. 40 The lower end of the fastening C is wider than its upper end, giving the device the form of a keystone or wedge, and the side flanges a gradually taper in depth toward the smaller end of the fastening. In the face of 45 the fastening C is cut the slot D, consisting of the enlarged portion e, the narrowed part d, and the entrance e. The upper end of the slot is made circular for convenience in use.

When it is desired to apply the neck tie or 50 scarf carrying the fastening C, the enlarged portion e of the slot D is inserted over the head of the collar-button, (if a small button

is used,) and the tie is then drawn down until the neck of the button passes into the smaller part d of the slot, when the ends of the shield may be placed underneath the laps of the collar; but when the fastening is to be secured upon a collar-button having an irregular-shaped head or a large thick head—such as the separable buttons necessarily employ—55 the lower open end of the fastening is slid over the head and drawn down until the neck of the button passes through the portions e c of the slot D and is held in the narrow portion d.

By making the fastening wedge-shaped both as to its width and depth it will securely retain the head of any usual button, and prevent any moving about of the tie. The head of a large button may have a bearing both 70 against the shield and the inner walls of the fastening.

It will appear obvious that by having the lower end of the fastening entirely open one is enabled to attach the tie to a thick-headed 75 button very readily, and that this could not be done with a different construction unless the slot D were unduly large and the device had much greater width and depth than the fastening I produce.

I am aware that various metallic pieces having slots have been secured to the shield of a necktie for attachment to the collar-button; but none of these, so far as I have been able to learn, are like the definite fastening 85 hereinbefore described, and hence

What I claim as new, and desire to secure by Letters Patent, is—

The wedge-shaped fastening C, closed at its upper end and sides and provided with 90 the button-slot D, as described, on its face, the lower end of the fastening being open, and said fastening being applied to the shield of a neck tie or scarf by lips cut thereon and penetrating the shield, substantially as set 95 forth.

Signed at New York, in the county of New York and State of New York, this 10th day of December, A. D. 1883.

JULIUS LOCHMAN.
